UNITED STATES PATENT OFFICE.

WASHINGTON OBENCHAIN, OF LOGANSPORT, INDIANA.

IMPROVEMENT IN BALANCED SLIDE-VALVES.

Specification forming part of Letters Patent No. **146,701**, dated January 20, 1874; application filed April 23, 1873.

To all whom it may concern:

Be it known that I, WASHINGTON OBENCHAIN, of Logansport, in the county of Cass and State of Indiana, have invented a new and valuable Improvement in Balanced Slide-Valves; and I do hereby declare that the following is a full, clear, and exact description of the construction and operation of the same, reference being had to the annexed drawings making a part of this specification, and to the letters and figures of reference marked thereon.

Figure 1 of the drawings is a longitudinal vertical section of my slide-valve and balance. Fig. 2 is a plan view with steam-chest cover removed. Fig. 3 is a side view with side of steam-chest removed.

This invention has relation to the slide-valve of a steam-engine; and it consists in the devices forming a steam-balance on the back of the valve, so arranged and constructed that the steam-pressure on said valve may be relieved to any desired amount, thereby preventing any unnecessary wear and friction.

In the accompanying drawings, the letter A represents a steam-chest of common construction, with steam-ports B B' and an enlarged exhaust-port, C. On the valve-face e slides the valve D, having the laps d^1 d^2 , and the lips c^1 c^2 in the exhaust-chamber d^3 . The width of the exhaust-port d, between the lips c^1 c^2 , is contracted with reference to, or less than that of, the exhaust-opening C of the valve-chest, for the purpose of holding the steam in the cylinder after the steam-opening has closed to gain the full benefit due to the expansion, and to exhaust at the proper time.

With the ordinary valve the steam cannot be cut off at any point of the stroke and at the same time the full benefit of the expansion secured; because, if the cut-off is varied to any extent, in certain positions of the valve the full effect of the expansion will be lost, owing to the want of length of the lips of the valve as compared with the span of the exhaust-opening.

With my valve the steam can be held longer without interfering with the proper exhaust.

The steam balancing devices are constructed in the following manner: To the top of the valve is bolted the base of a cylinder, E, having a closed top. Surrounding the cylinder E

is the balance-ring F, which is provided with an external flange, f, and a recess or groove, f^1 , around its inner upper edge. This recess is designed to insure the pressure of the ring F against the wall of the valve-chest. The cylinder E is also recessed to receive the packing-ring H, which lies in contact with the inner wall of the balance-ring, and keeps the joint steam-tight. The balance-recess f^1 should be sufficiently large to cause the steam to press the balance-ring against the face of the steam-chest cover G, thus making a steam-tight joint without the use of springs or set-screws. In this manner the operation of the balance-ring is made automatic, and the valve is relieved from pressure. Two small springs, i, are seated on the base e of the cylinder E, under the lower edge of the balance-ring, within the bolts e' e'. These serve to hold the balance-ring up to its place when steam is shut off, thereby preventing this ring from slamming violently against the steam-chest cover G when steam is suddenly put on. These springs are not designed to have sufficient power to cause friction between the balance-ring and steam-chest cover. The pipe h, through the steam-chest cover, communicates with the balance-chamber f^2 , between the top of the cylinder E and the steam-chest cover, and with the balance-recess f^1 of the balance-ring.

It is better to have a small perforation, z, leading from the inside of the cylinder E, through its wall, to the packing-ring, as its action is thus accelerated by the steam-pressure.

What I claim as my invention, and desire to secure by Letters Patent, is—

The combination, with a steam-valve and valve-chest, of the balance-cylinder E, closed at top, the balance-ring F, the flange f, forming a part of said balance-ring, and the air recess or groove f^1 on the inner edge of said ring, communicating with the balance-chamber f^2 between the balance-cylinder and the valve-chest wall, substantially as specified.

In testimony that I claim the above I have hereunto subscribed my name in the presence of two witnesses.

WASHINGTON OBENCHAIN.
